UNITED STATES PATENT OFFICE.

WILLIAM HOWARD BOUGHTON, OF CLEVELAND, OHIO, ASSIGNOR OF ONE-HALF TO LOUIS L. KROPP, OF CLEVELAND, OHIO.

SMOKING-PIPE CLEANER.

No. 888,688.

Specification of Letters Patent.

Patented May 26, 1908.

Application filed October 31, 1907. Serial No. 400,055.

To all whom it may concern:

Be it known that I, WILLIAM H. BOUGHTON, a citizen of the United States, residing at Cleveland, in the county of Cuyahoga and 5 State of Ohio, have invented a new and useful Smoking-Pipe Cleaner, of which the following is a specification.

This invention has reference to improvements in cleaner attachments for tobacco 10 pipes, and its object is to provide a cleaner designed to remain in the pipe while the latter is in use, and to be capable of manipulation in such manner as to remove any accumulation in the pipe bowl or stem which it 15 is desirable to remove.

The invention comprises a semi-tubular structure adapted to extend through the pipe bowl and into the stem with a continuation adapted to be passed through the pipe bowl 20 and snugly fit the same diametrically opposite the stem, the said continuation terminating in a finger hold of suitable shape, so that the attachment may be rotated on a longitudinal axis and also withdrawn from or inserted into the pipe, as the case may be. 25

The invention will be best understood by reference to the following detail description, taken in connection with the accompanying drawings forming part of this specification, 30 in which drawings,

Figure 1 is a longitudinal section, with parts in elevation, of a pipe with the cleaner attachment in place. Fig. 2 is a section on the line $x-x$ of Fig. 1, looking toward the stem. 35 Fig. 3 is a perspective view of the finger attachment on an enlarged scale.

Referring to the drawings, there is shown the bowl 1, stem 2, and a portion of the mouthpiece 3 of an ordinary pipe. These 40 several portions of the pipe are shown in a more or less conventional manner, since the type or style of tobacco pipe is not at all material to my invention, because the invention is adapted for use with a great variety of 45 types and styles of tobacco pipes.

In the body of the bowl 1 opposite and in line with the bore of the stem 2, there is an orifice 4 for the reception of the attachment, as will presently appear.

50 The attachment comprises a cylindrical section 5 with a semi-tubular extension 6 on one side of the cylindrical section 5, and a finger-hold 7 on the other side. The cylindrical portion 5 is of such size as to snugly fit 55 the opening 4 in the pipe bowl, and the semi-

tubular section 6 is of sufficient length to extend across the pipe bowl and into and nearly through the stem 2, while the finger-hold 7 is exterior to the pipe bowl. Now, when the attachment is inserted in a pipe, 60 the open side of the tubular section 6 permits free access of air, or free circulation, through the stem 2, whether this open side is placed uppermost or not. Now, let it be supposed that the pipe has been used for a considerable 65 time and there is considerable choking of the bore of the stem by accumulations of deleterious material, it is then only necessary to rotate the attachment upon its longitudinal axis two or three times when the edges of the 70 semi-tubular section 6, which section should snugly fit the bore of the stem 2, will scrape off any accumulations on the inside of the stem and cause them to be deposited in the interior of the said extension 6. Now, this 75 section may be withdrawn with the scraped off material in it and then may be cleansed, and later reintroduced into the pipe. There is thereby provided not only a means for loosening accumulations, but for collecting 80 the same and for removing them from the pipe stem and from the bowl of the pipe at practically one operation.

It is to be noted that the section 5 has been described as cylindrical. It is, in fact, 85 slightly tapering so as to fit snugly into the opening 4 and to bind therein when desired. It is not necessary to remove the structure from the pipe unless the stem becomes so choked as to render the removal of the 90 cleaner imperative. Usually, the simple rotation of the device is sufficient to open up the draft.

The end 7 is made globular and is perforated so that it may remain cool, but it may 95 be otherwise constructed and may be made either plain or ornamental to befit the type of pipe with which the attachment is used.

By the term semi-tubular, as applied to the section 6, it is not intended to mean that 100 this section is strictly semi-tubular, for it may embrace an arc greater or less than 180° . Its exterior diameter is substantially that of the bore of the pipe stem, and it will then act to scrape away accumulations, since 105 the edges will act as cutting edges.

I claim:—

A tobacco or smoking pipe having the stem terminating at one side of the bowl above the bottom thereof and the other side 110

of the bowl opposite the stem provided with an orifice and a cleaning attachment for the pipe stem having a tapering portion adapted to snugly fit the orifice in the pipe bowl opposite the stem, and a semi-tubular portion extending from the tapering portion and adapted to enter the stem of the pipe, said semi-tubular portion extending across the bowl of the pipe above and separated from the bottom thereof, the attachment being also pro-

vided with a manipulating head exterior to the pipe bowl.

In testimony that I claim the foregoing as my own, I have hereto affixed my signature in the presence of two witnesses.

WILLIAM HOWARD BOUGHTON.
